UNITED STATES PATENT OFFICE.

MANUEL REY GARCIA, OF LEAVENWORTH, KANSAS.

LAUNCHING APPARATUS FOR LIFEBOATS.

1,363,036.

Specification of Letters Patent. Patented Dec. 21, 1920.

Application filed October 21, 1919. Serial No. 332,154.

To all whom it may concern:

Be it known that MANUEL REY GARCIA, a citizen of Spain, residing at Leavenworth, in the county of Leavenworth and State of 5 Kansas, has invented new and useful Improvements in Launching Apparatus for Lifeboats, of which the following is a specification.

The object of the invention is to provide 10 a safety device capable of application to vessels particularly of the type designed for passenger travel whereby in case of emergency the life boats may be expeditiously and safely launched under such conditions 15 as to guard against capsizing or injury to the boats, particularly when the launching must be effected while a rough sea is running, and whereby the boats may as readily be hoisted to their normal positions with 20 reference to the gunwales of the boat or ship as similar boats usually occupy when supported by davits as in the ordinary practice.

To this end the invention consists in a construction and combination of parts of 25 which a preferred embodiment is illustrated in the accompanying drawings, it being understood that changes in forms and proportions may be resorted to within the scope of the claims without departing from the principles involved.

In the drawings:

Figure 1 is an end view of the apparatus as seen when the boat is in its normal position while the vessel is in motion.

35 Fig. 2 is a side view of the same.

Fig. 3 is a detail view in section of a portion of the landing platform or stage to show the means for retaining the same in a normal or housed position and also the 40 means for lowering the same when required.

Figs. 4 and 5 are respectively side and edge views of the supporting grapple which is connected with the hoist pole.

45 Figs. 6 and 7 are respectively side and edge views of the castoff hook.

Fig. 8 is a view of the retaining loop or ring of the castoff hook.

Fig. 9 is a perspective view of the upper end of one of the platform or staging guides.

50 Figs. 10 and 11 are respectively perspective and plan views of the end portion of

one of the traveler bars which traverse the stationary guides or tracks secured to the vessel's side.

Fig. 12 is a detail end view of a portion 55 of the platform or staging to show one of the horses or chuck blocks by which the boat is seated on the platform.

Fig. 13 is a detail view in side elevation of 60 one of the bolt retaining arms and a portion of the connected retaining chain by which accidental displacement of the bolt when seated is prevented.

Fig. 14 is a detail sectional view to show 65 the means whereby the supplemental platform is connected with the main platform and the connection of the buoy cables thereto.

Essentially the apparatus consists of 70 parallel tracks or guides 20 preferably secured in vertical position and in parallelism to the side of the vessel indicated at 21, and which may be secured to the exterior surface thereof, and upon which is mounted for vertical movement a platform 75 or staging 22 adapted to support a life boat 23 of which obviously any desired number, depending on the size of the platform, may be supported for the simultaneous launching operation. The platform or staging 22 is 80 provided with a depending traveler frame 24 consisting in the construction illustrated of a plurality of parallel bars 25 headed as shown at 26 in Figs. 10 and 11 to engage slots 27 in the guides or tracks 20, suitable 85 diagonal bracing elements 28 connecting said traveler bars to afford the necessary strength and rigidity.

A davit or hanger post 29 is disposed in an inclined position to project terminally 90 over the path of the platform or staging 22, the outer end thereof being supported by a post 30, and connected therewith by means of a bolt 31 or the equivalent thereof is a hanger 32 consisting of an upper hook 33 95 for engaging an eye 34 in the lower end of the bolt 31, and a lower hook 35 with which is connected a suspending chain 36 leading to and engaged by a castoff hook 37 attached as at 38 to the platform or staging. Said 100 chain is designed to hold the platform or staging in its normal or housed position

with the boat supported thereon, and when it is desired to lower the boat for launching the castoff ring or loop 39 shown in detail in Fig. 8 may by means of the trip chain 5 or cord 40 be disengaged from the hinged tongue 41 of the castoff hook so as to release the eye 42 at the lower end of the supporting chain. The lowering of the platform with the boat, and obviously the 10 turn of the same to the normal or housed position is effected by means of a cable 43 passing around fall blocks 44 and 45 of which the former is engaged with an eye 46 in the hook 33 of the supporting shackle 15 32 while the latter is connected by means of an eye 47 with the platform. It will be understood that a winch (not shown) may be employed for controlling the cable 43 or for controlling a plurality of hoisting cables connected with as many platforms or 20 stages as may be desired, so that a plurality of boats may be simultaneously launched from different points on the vessel.

From the traveler bars 25 located beneath 25 the plane of the platform or stage 22 there extend diagonal braces 48 to sustain the weight of the platform and its load, and carried by the platform are the horses or chuck blocks 49 combining at the bow and 30 stern of the life boat to form seats for the reception of the hull of such boat, retaining chains 50 being connected with retainer arms 51 extending transversely from the ends of the horses or chuck blocks and connected over the life boat by means of cast-off hooks 52. When a boat is about to be lowered these retaining chains may be loosened as indicated in Fig. 12 to permit of the floating of the boat as soon as it 35 reaches the water, the purpose of said chains being obviously to prevent the accidental displacement of the boat from the seats formed by the horses when the platform or staging is in its normal position as indicated in Figs. 1 and 2.

The lower ends of the guides or tracks which extend below the plane of inward curvature of the hull of the vessel are braced as shown at 53 so as to positively guide the 50 platform and the traveler bars connected therewith to a depth sufficient to float the life boat free from the rests or seats formed by the horses or chuck blocks.

Suspended beneath the main platform or 55 staging is a supplemental platform 54 designed to act as a fender to prevent injury to or excessive jarring of the main platform as the latter is lowered with the boat, said supplemental platform being connected 60 with the main platform by means of bolts 55 extending through spacing tubes 56, and connected with the supplemental platform are cables 57 extending through guide tubes 58 on the edges of the main platform and 65 connected to cork floats or buoys 59 which

normally may be housed between the planes of said auxiliary and main platforms, but which when the apparatus is submerged float to the surface of the water at the front and rear edges of the platform or staging 70 to serve as a guide to the occupants of the boat in positioning the latter above the platform when it is desired to hoist the boat to its normal or elevated position as indicated in Figs. 1 and 2. 75

What is claimed is:

1. An apparatus for the purpose described having parallel tracks arranged vertically at the sides of a vessel hull, a platform or staging mounted to operate upon said guides 80 or tracks and adapted for movement to a point below the water line, chuck blocks carried by the platform or staging to form a seat for a life boat, retaining arms extending laterally from said chuck blocks, retaining chains connected with said retaining arms for extension over a seated life boat to retain the same in position in the seat, said chains being connected at their free ends by castoff hooks, and means for lowering and raising the platform. 90

2. An apparatus for the purpose described having parallel vertical guides for arrangement at the side of a vessel hull, a platform or staging having traveler bars mounted upon said tracks or guides, a davit bar supported by the vessel deck and extending terminally over said platform or staging, a shackle connected with the projecting end of said davit bar, a supporting chain extending from said shackle, a castoff hook carried by the platform for engagement with the free end of the chain for supporting the platform in its normal position, means upon the platform for seating and retaining a life boat, and means for lowering and raising the platform. 100

3. An apparatus for the purpose described having parallel vertical tracks or guides for arrangement at the sides of a vessel hull, a 110 platform having traveler bars mounted in said tracks or guides and provided with means for supporting a life boat, a davit bar terminally extending from the vessel deck over the plane of a platform, a supporting chain carried by the davit bar and having a castoff connection with the platform for supporting the latter in its normal position, and a hoisting apparatus including a cable and fall blocks connected respectively with said davit bar and platform for lowering and raising the latter. 115

4. An apparatus for the purpose described having vertical parallel tracks or guides, a platform provided with traveler blocks 125 mounted in said tracks or guides and supporting horses or chuck blocks forming a seat for a life boat, means for retaining a boat in said seat, a supplemental platform suspended beneath the plane of the first- 130

named platform and spaced therefrom, indicator buoys having floats connected by cables extended through guides at the inner and outer edges of the first-named platform
5 and adapted to be housed between the planes of said platforms, means including castoff

hooks for supporting said platforms in their normal or elevated position, and hoisting mechanism for lowering and raising the platform.

10

In testimony whereof I affix my signature.
MANUEL REY GARCIA.
